FUEL MIXING APPARATUS

Filed Dec. 1, 1927

FIG. 2.

This technical drawing illustrates a device with several labeled components. The top left shows a perspective view of a curved tube assembly with a flange and a circular base. The top right is a cross-sectional view of a cylindrical component with internal parts labeled 10, 11, 12, 13, 14, 15, 16, 17, 18, 19, 20, 21, 22, 23, 24, 25, 26, 27, 28, and 29. The bottom left is a detailed view of a coiled spring or coil assembly with components labeled 31, 32, 33, 34, 35, 36, 37, and 38. The bottom right contains the text "Inventor" and "W. F. Fenzel" along with a signature.

UNITED STATES PATENT OFFICE

WILLIAM F. FENZEL, OF CLEVELAND, OHIO

FUEL-MIXING APPARATUS

Application filed December 1, 1927. Serial No. 237,057.

This invention relates to improvements in fuel treatment and supply apparatus for internal combustion engines, and has as its essential and primary object the increasing 5 of the efficiency of the motor.

A further object is the increasing of such efficiency with fuel of lower grade or inferior quality.

With these and other and more detailed 10 objects in view, as will in part hereinafter become apparent and in parts be stated, the invention comprises certain novel constructions, combinations, and arrangements of parts as subsequently specified and claimed.

15 In the accompanying drawings—

Figure 1 is a view in side elevation, somewhat diagrammatic, of an internal combustion motor equipped with an embodiment of the present invention.

20 Figure 2 is an enlarged, detail, sectional elevation of a structure embodying the features of the present invention.

Referring to the drawings by numerals, 1 indicates an internal combustion motor of 25 any well known or conventional type having the usual exhaust manifold 2 discharging into the exhaust pipe 3. The customary intake manifold 4 communicates with the source of fuel supply incorporating the features of the 30 present invention. The details of connection between such fuel supply and the manifold 4 are susceptible of a wide range of variance, as will become obvious. One specific form of 35 such connections is illustrated in the drawings and comprises the usual clamping flanges 5 fixed, respectively, to the intake manifold and the carburetor body or fuel supply. The carburetor flange in the structure illustrated in the drawings is formed integral with, or 40 otherwise fixed to, the throat or discharge tube 6 of the mixing chamber 7. A throttle valve 8 is pivoted in the customary manner in the throat 6 and provided with a clamp 9 and other linkage, not illustrated, for the 45 usual carburetor throttle control. The mixing chamber 7 is preferably globular, but may be otherwise shaped, and is provided in its upper portion with a spider 10 carrying a pendent guiding pin 11 on which is slidingly 50 mounted a mixing and control valve 12. An

appropriately tensioned spring 13 is coiled about the upper portion of the valve 12 so as to rest at its lower end against the valve and contact at its upper end against the spider 10, and thereby stress the valve 12 downward 55 to its seat. The under face of the valve 12 is formed centrally into a pendent inverted cone 14 which flares upwardly and blends into the body of the valve 12 with an encircling depression 15 formed in the under 60 face of the valve at the point of union of the cone 14. The lower portion of the housing 7 is open to form a downwardly opening passageway for accommodating the valve 12, and the housing 7 is provided with a flange 16 65 bolted or otherwise appropriately clamped to a flange 17 of the air intake chamber 18. The chamber 18 has a lateral port 19 provided with a control valve 20 similar in construction and arrangement to the throttle 8 and appropriately connected by linkage 21 for easy and ready manual or foot control of the operator. The air intake chamber 18 may be a casting, or may be otherwise constructed, and is provided with a pendent chamber 22 closed by a 70 web 23 across its top and thus separated from the intake portion of the housing 18. A fuel supply tube 24 leads from within the chamber 22 to a point just beneath the valve 12. The lower terminus of the tube 24 is preferably 75 ground to a valve seat 25 adapted to receive the needle valve 26 threaded through the bottom of the chamber 22. Needle valve 26 is provided with the usual or appropriate gland 27 and with an operating handle 28 accessible 80 from the exterior for adjusting the valve 26 relative to its seat 25 for controlling the possible quantity of gas or other fluid to be permitted to pass up the tube 24. The upper terminus of the tube 24 is ground to form a 85 valve seat 29 located and formed to receive the cone 14 as a needle valve, whereby, when the parts are at rest, the tension of spring 13 will cause the valve 12 to remain seated on the seat 29 and shut off all supply of fuel. 90

A fuel delivery tube 30 leads laterally into the chamber 22, and is preferably formed into a coil 31 designed to extend the path of travel of the fuel in a relatively short compass of 95 space for facilitating application of heat. A 100

In operation, hydrocarbon fuel, such as gasoline, is supplied through pipe 35 and connected parts, to chamber 22, and these parts will stand filled with the liquid while the motor is cold and not in operation. When it is desired to start the operation of motor 1, the primary shifting of the pistons thereof, as by the starter motor or otherwise, will cause that imbalanced pressure which results in the lifting of piston 12 from its seat and the immediate fuel from the tank.

immediately from its seat and

ther means of insuring an ample discharge through the pipe 33, the intake end of pipe 33, that is the end communicating with the manifold 2, may be provided with an appropriate 5 deflector plate or baffle, such as seen at 38, to intercept the burnt products advancing along the manifold 2 and deflect them into the pipe 33. The baffle 38 may be fixed to the end of the pipe 33 in any appropriate manner 10 or, as illustrated, may be produced by cutting away a portion of the pipe itself and leaving that portion best located for deflecting the gases into the intake end of the pipe.

What is claimed is:—

15 1. In fuel mixing apparatus wherein vaporized fuel and air are mixed, the combination of an air intake chamber, a mixing chamber above and in direct communication with the air intake chamber, a gaseous fuel 20 chamber contacting with the air intake chamber and sealed from communication therewith, a discharge tube extending upwardly from the gaseous fuel chamber and opening toward the mixing chamber at the place of 25 communication of the air intake chamber with the mixing chamber, the cross sectional area of the discharge tube being relatively small with respect to that of the gaseous fuel chamber, an imperforate valve extending 30 across and substantially closing the communication between the air intake chamber and mixing chamber and arranged above the discharge end of the gaseous fuel discharge tube and having a portion adapted to engage 35 and close said discharge end, and means additional to said valve for varying the discharge through said tube.

2. In fuel mixing apparatus wherein vaporized fuel and air are mixed, the combination of an air intake chamber, a mixing chamber above and in direct communication with the air intake chamber, a gaseous fuel chamber contacting with the air intake chamber and sealed from communication therewith, a 40 discharge tube extending upwardly from the gaseous fuel chamber and opening toward the mixing chamber at the place of communication of the air intake chamber with the mixing chamber, the cross sectional area of the 45 discharge tube being relatively small with respect to that of the gaseous fuel chamber, an imperforate valve extending across and substantially closing the communication between the air intake chamber and mixing 50 chamber and arranged above the discharge end of the gaseous fuel discharge tube and having a portion adapted to engage and close 55 said discharge end, and a valve at the lower end portion of the gaseous fuel discharge tube for varying the discharge through said tube.

In testimony whereof I affix my signature.
WILLIAM F. FENZEL.
